UNITED STATES PATENT OFFICE

THOMAS J. WALLS, OF WAYNESVILLE, NORTH CAROLINA

DESIGN FOR A SERVICE TRAY

Application filed October 8, 1931. Serial No. 41,342. Term of patent 3½ years.

To all whom it may concern:

Be it known that I, THOMAS J. WALLS, a citizen of the United States, residing at Waynesville, in the county of Haywood and State of North Carolina, have invented a new, original, and ornamental Design for Service Trays, of which the following is a specification, reference being had to the ac-

companying drawing, forming part thereof.

The figure is a perspective view of a service tray showing my new design.

I claim:

The ornamental design for a service tray as shown.

THOMAS J. WALLS.
